UNITED STATES PATENT OFFICE.

ROBERT C. WALTER, OF DETROIT, MICHIGAN, ASSIGNOR TO DODGE BROTHERS, INC.,
OF DETROIT, MICHIGAN, A CORPORATION OF MARYLAND.

DOOR-OPERATING MECHANISM.

Application filed January 14, 1926. Serial No. 81,353.

This invention relates to door operating mechanism and more particularly to mechanism dependent upon the movement of a movable body for controlling swinging doors 5 and the like.

While many advantages of the present invention are obtained when the same is used in connection with any type of swinging closures nevertheless the invention finds particular 10 utility in connection with swinging doors or closures of an oven or other heated compartment through which objects are adapted to be moved. It is essential, particularly in connection with drying ovens and the like, 15 that the door-ways thereof be kept closed so as to maintain the entire oven or compartment at a uniform temperature.

In drying ovens and the like it is the practice to cause the objects, such for instance as automobile bodies, to travel 20 through the ovens or drying rooms and to so regulate the speed thereof that such bodies remain within the ovens a predetermined desired length of time. The bodies 25 thus being conveyed through the oven are usually spaced apart and emerge from the oven at separated intervals between which times it is highly desirous that the exit doors be maintained closed. Inasmuch as the 30 instants of emergence of several bodies are not always uniformly spaced apart it is impractical to provide automatic periodical- 35 ly operating mechanism for controlling the exit doors and, for like reasons and also for economical reasons it is impractical to manually control the exit doors.

It has therefore, been found to be more efficient to provide a door operating mechanism controlled and operated solely by the 40 moving object so that irrespective of the time elapsing between the emergence of the objects from within the oven the doors will be properly controlled. It is essential however, in connection with ovens used in drying 45 automobile bodies that the doors be so controlled as to consistently clear the bodies as they pass therethrough so as to positively eliminate the danger of marring or otherwise defacing the finish of the bodies. Thus 50 the problem presents itself of providing a door controlling mechanism operated by and only upon the emergence of a body and so controlling the doors as to insure a complete clearance between them and the automobile 55 body or other object passing therethrough.

My invention contemplates an arrangement wherein the objects and advantages mentioned above are fully and efficiently accomplished in a mechanically and commercially satisfactory manner. The invention 60 is furthermore distinguished by its simplicity which insures its durability and mechanical efficiency.

The various objects, advantages and fundamental structural features as well as 65 novel details of construction of one illustrative embodiment of the invention will be made more apparent as this description proceeds especially when considered in connection with the accompanying drawings 70 wherein:

Figure 1 is a fragmentary horizontal sectional view of an oven or other drying compartment with my improved closure operating means associated therewith;

Figure 2 is a vertical sectional view taken substantially on the plane indicated by line 2—2 in Figure 1, and;

Figure 3 is a fragmentary perspective view of one end of the truck.

While the invention will be described as used in connection with a drying oven or room for drying objects such as automobile bodies it will become readily apparent to those skilled in the art that the principles of the invention are applicable to closures for use in connection with numerous other types of apparatus. However, in the illustrated embodiment herein disclosed I have shown fragmentarily the exit end of an 90 oven or drying room 10 which includes a bottom or floor portion 11, side walls 12 and an open end 13 through which the automobile bodies or other objects indicated in dotted lines at 14 emerge. The path of travel of the objects is preferably, although not necessarily, defined by a track-way comprising track members 15, one of which is preferably flanged for guiding purposes and associated with this track I preferably employ a mobile member such as a truck 16 or movable body provided with wheels which engage the track members 15. In drying 95 automobile bodies it is the practice to mount the automobile body 14 on the truck or movable body 16 whereby the same is caused to travel longitudinally through the drying chamber 10.

The truck or movable body 16 is provided 110 at its forward and rear ends thereof with

projecting elements constituting bumpers 17 of identical construction and projecting in a horizontal plane as illustrated. Each bumper is shaped to provide a forward portion 18 substantially parallel with the adjacent end of the truck 16 and with diverging side portions 19.

The exit opening 13 of the drying compartment 10 is adapted to be closed by a pair of swinging doors 20, hingedly connected at their outside vertical edges to the side walls 12 of the drying room by means of spring hinges or the like 21. In this connection however, it is to be noted that the spring hinges are herein described merely as indicative that the doors 20 are normally closed, it being therefore quite obvious that any other means such as weights, or the like may be employed for maintaining the doors in their closed position such as illustrated in Figure 1. It is preferable that the doors be simultaneously operated and to accomplish this they are interconnected by means of a link 22 pivoted as at 23 on the one hand to a bracket 24 projecting inwardly from one of the doors 20 and on the other hand pivotally connected as at 25 to a bracket 26 projecting outwardly from the other door 20. Therefore a swinging movement imparted to either of the doors will cause a similar movement simultaneously of the other door. The connecting link 22 is preferably, although not necessarily arranged adjacent the top of the doors so as to clear the door operating mechanism about to be described.

Rigidly secured to one of the doors, and in a plane coincident with the horizontal plane of the bumpers 17, is an element 27 which in the form herein illustrated comprises a non-flexible strip of metal bent into a substantial V or wedge shape and secured to the inner face of one of the doors 20 as indicated at 28. That portion of the element indicated at 29 constitutes merely a reinforcing or supporting member for the extremity of the inclined portion 30. It will be noted that the surface of the portion 30 extends laterally or substantially transversely of the doors and door opening and is inclined with reference thereto and in a general direction toward the approaching body carried by the truck 16. The dimension or length of the inclined surface 30 and its degree of inclination with reference to the door opening is so selected that it will be engaged by the forwardly extending bumper 17 and these two elements will function to move the doors to a position to permit the emergence of the truck or movable body 16 and the automobile body 14 mounted thereon.

As mentioned, it is essential that the doors 20 be swung to such a position as to afford ample clearance for the automobile body 14, which it is noted, projects laterally a consid-

erable distance from the sides of the truck 16. The initial points of the engagement of the bumper 16 and surface 30 of the element 27 is indicated in full lines in Figure 1. During the advancement of the truck 16 the corner of the bumper will ride outwardly of the surface 30 toward the extremity 31 thereof and upon a continued movement the extremity of the element 27 will travel along the surface of the bumper then outwardly along the inclined surface 19 to the periphery of the truck and during the intermediate stages of emergence the extremity 31 of the element 27 will transiently engage the adjacent side 32 of the truck 16. During this position of the truck the doors 20 will amply clear the sides of the automobile body 14 as they will at that moment be open more widely than indicated by the dotted line position in Figure 1 wherein they have started to move into closing position. As will be apparent from this dotted line position of the parts, the extremity 31 as it leaves the peripheral surface 32 of the truck will then engage the inclined surface 19 of the rear bumper 17 and during the continued movement of the truck 16 this extremity will ride rearwardly upon the surface 19 until the extremity 31 clears the rear end of the bumper whereupon the spring hinges 21 or other door closing means will move the doors to closed position. It is interesting to note that during the closing movement of the doors the rear bumper 17 will maintain the desired clearance between the doors and the rear portion of the body 14.

From the foregoing it will be apparent that this invention contemplates simple but effective means for operating the doors which means depends solely for its activity upon the approach and emergence of the object traveling through the doors and that at every moment during the emergence of the object the doors will remain in a position affording ample clearance between them and the object passing therethrough. It will also be obvious, as indicated hereinbefore, that the invention may be associated with closures used in various other connections and furthermore that the details of construction may be materially altered without departing from the spirit and scope of the invention. Consequently to this end reservation is made to make such changes in either the essential or non-essential details of the invention as may come within the purview of the accompanying claims.

What I claim as my invention is:

1. The combination with a movable body, of normally closed swinging closures and means on said body and a member on said closures engaging during the emergence of said body for controlling the closures to clear the body.

2. The combination with a pair of inter-

connected swinging doors, of a movable body adapted to move through said doors and a member on one of said doors engageable by said movable body for operating said doors to clear said movable body as the latter passes therethrough.

3. The combination with a doorway, a pair of interconnected swinging doors therefor and a body movable through said doorway, 10 of an inclined substantially transversely extending element secured to one of said doors and projecting toward the movable body, and means on said body, projecting forwardly and rearwardly thereof and engaging said 15 element for controlling said doors in advance of and after the emergence of said body through said doorway.

4. The combination with a doorway and a pair of interconnected swinging doors, of an 20 element carried by one of said doors, said element extending substantially transversely of said doorway and inclined with respect to said door; the length and degree of inclination of said element being so selected with 25 reference to said doors that a body moving through said doorway will engage said element to control said doors in advance of and after the emergence of said body.

5. The combination with a doorway and 30 a pair of normally closed interconnected swinging doors, of an element carried by one of said doors, said element extending substantially transversely of said doorway and inclined with respect to said door; the length and degree of inclination of said element being so selected with reference to said doors 35 that a body moving through said doorway will engage said element to control said doors in advance of, during and after the emergence of said body.

40 6. In a door operating mechanism a pair of interconnected doors and a laterally extending element secured to one of said doors and inclined relatively to the plane of the door, said element projecting toward an emerging body and engageable by said body for controlling the doors in advance of and after the passage of the body through the doorway.

50 7. The combination with a swinging door, of a laterally directed inclined element carried by said door engageable by a body movable through the door opening closed by said door for controlling the door in advance of and after the emergence of said body.

55 8. The combination with a doorway, a

swinging door and a body to be moved through said doorway, of a door operating element carried by said door and means on said body engaging said element for controlling said door in advance of and after the emergence of said body.

60 9. The combination with a doorway, a pair of simultaneously movable normally closed swinging doors and a body adapted to be moved through said doorway, of a door operating element carried by one of said doors and means on said body engaging said element for controlling said doors in advance of and after the emergence of said body.

65 10. The combination with an enclosure having a doorway, swinging interconnected doors for said doorway, and a body movable from within said enclosure through said doorway, of door operating means including 70 an element mounted on the inside of one of said doors and presenting an inclined substantially transversely extending surface, and means projecting forwardly and rearwardly of said body and engaging said element for controlling said doors in advance of and after the emergence of said body through said doorway.

75 11. The combination with an enclosure having a doorway, normally closed swinging 80 interconnected doors for said doorway, and a body movable from within said enclosure through said doorway, of door operating means including an element mounted on the inside of one of said doors and presenting an 85 inclined substantially transversely extending surface toward said movable body, and means projecting forwardly and rearwardly of said body and engaging said element for controlling said doors in advance of and 90 after the emergence of said body through said doorway.

95 12. The combination with an enclosure having a doorway, normally closed swinging 100 interconnected doors for said doorway, and a body movable from within said enclosure through said doorway, of door operating means including an element mounted on the inside of one of said doors and presenting an inclined substantially transversely extending 105 surface and means arranged peripherally of said body and engaging said element for controlling said doors prior to, during, and after the passage of said body through said doorway.

110 In testimony whereof I affix my signature.
ROBERT C. WALTER.
